UNITED STATES PATENT OFFICE.

GUSTAF EMANUEL JOHANSON, OF SUNDSVALL, SWEDEN.

SORTING DEVICE FOR SAWN WOOD.

1,349,836.

Specification of Letters Patent. Patented Aug. 17, 1920.

Application filed November 10, 1919. Serial No. 337,103.

To all whom it may concern:

Be it known that I, GUSTAF EMANUEL JOHANSON, a citizen of the Kingdom of Sweden, residing at Sundsvall, Sweden, have 5 invented new and useful Improvements in Sorting Devices for Sawn Wood, of which the following is a specification.

This invention relates to sorting devices for sawn wood of the type in which the wood 10 pieces, as for instance deals, boards or the like, are transported along a feeding runway below which collecting compartments for the different sorts are provided, movable devices being arranged in the runway and 15 adapted to effect automatically the sorting.

The object of the invention is to provide a sorting device of this kind by means of which the sawn wood may be sorted automatically into groups according to thickness, width, length or quality, it being 20 possible to effect the sorting according to one or more or all of said properties.

This object is obtained according to the invention by so placing the movable devices arranged in the runway that they are actuated by the longitudinal side of the sawn wood lying transversely in relation to the longitudinal direction of the runway, the latter being preferably provided at the beginning 25 with marks or stops serving to determine the position of the wood pieces in their longitudinal direction relatively to some of the movable devices effecting the sorting.

Some embodiments of the invention are 30 illustrated in the accompanying drawings in which—

Figure 1 is a side view of a sorting device arranged according to the invention. Fig. 2 40 is a side view of a modified embodiment thereof. Fig. 3 is a plan view of the device.

Figs. 4 to 13 inclusive illustrate on an enlarged scale several details of the device.

Relating to Figs. 1 to 3, 1 designates a 45 series of feed chains or the like provided with catchers 4 and running along a runway in the direction of arrow *b* in Fig. 1 around chain wheels secured to shafts 2 and 3. 11 is a circular saw placed near one 50 edge of the runway. 12 is another circular saw disposed, if necessary, near the opposite edge of the runway. Below the runway collecting compartments 9 and 10 are located, each adapted to receive one sort of the sawn 55 wood. Each compartment is provided at the top in the runway with an aperture

having devices so arranged that the wood pieces intended for the compartment may drop down into the same by actuating the said devices, whereas the wood pieces not intended for the compartment pass the aperture.

Feed chains 5 running above the collecting compartments are provided with catchers 8 and driven by chain wheels 6 and 7 in the direction indicated by arrow *c* in Fig. 1. Each compartment is provided with a shaft 15 forming right angles with the direction of movement of the wood pieces. Secured to said shafts are arms 14^a in compartment 9, Fig. 6, and 16 and 14 in the compartments 10, Figs. 4 and 5 as well as arms 16, 17, 18, 19, 20 and 21 in the compartments 10, Figs. 4 and 5. Besides, the shaft 15 in compartment 9 is provided with an arm 13. In the rest position of the arms 14^a their free ends are raised above the plane of the runway, whereas the arm 13 is so curved that its free end is situated below said plane and provided with a bent portion extending above the same plane (Fig. 6). In the rest position of the arms 14 they are situated in the plane of the runway thus closing the admission to the compartments 10, the arms 16 to 21 secured to the same shafts as the arms 14 having their free ends raised above the plane thus allowing the wood pieces to enter the space below said ends.

Placed in the compartments 10 are carriages running on rails and intended for loading of the wood. The compartment 9 contains circular saws 22 for cutting the wood dropping down therein.

The device described operates as follows:

A in Figs. 1 and 2 is the end of the device 90 where the wood pieces 25 are supplied by any transporting device (not shown) in the direction of arrow *a* (Fig. 3) for instance directly from the sawing machine or any other place. The wood pieces then drop down onto a table 24 or immediately onto the feed chains 1. The table is to be preferred to the chains, because in the former case the workman standing at D (Fig. 3) will be able to place one wood piece at the time on the chains. Rollers extending across the table are preferably provided and adapted to facilitate the movement of the wood in the longitudinal direction of the table. The wood pieces reach the sorting device with the top *x* foremost and consequently with the root-end *y* directed toward the place D.

The deal or board is placed by the workman on the chains in such manner that the root-end is cut by the circular saw 11 with the least possible waste wood. On the assumption that no circular saw 12 be provided, the wood piece is then moved longitudinally by the workman in such manner that the cut end will be situated in any one of several lines 26^a, for instance marked by stops or 10 the like, which, if desired, may be adjustable and serve to determine in what collecting compartment the wood piece is to be dropped. If the wood piece shall drop for instance in the compartment designated by 15 10^a in Fig. 1, it is moved to the stop 26^a corresponding to the arm 17. The wood piece is then first moved to the arm 13 in compartment 9, said arm, owing to its shape described above, being pressed downward thus 20 turning the arms 14^a downward so as to close the admission to compartment 9 and causing the wood piece to pass by said compartment. The arm 16 in the next compartment 10 being situated outside the path of movement 25 of the wood piece will not be actuated, and consequently the wood piece will pass over the arms 14 closing the admission to said compartment. The wood piece then reaches the arm 17 which, while being raised, raises 30 the corresponding arms 14, the wood piece then dropping down into the compartment 10^a.

In special productions it will sometimes happen that the pieces sawed out of the timber are not squared throughout the whole length, but are first cut to shorter pieces, each of which is then squared separately. In this case such wood is suitably collected in a place where the cutting and the squaring can take place. To this purpose the compartment 9, provided with the circular saws 22, is disposed. The wood pieces intended for this compartment are preferably so placed that they after having passed the 45 circular saw 11, enter without further handling below the raised arms 14^a without contacting the arm 13 and then drop down into the compartment 9 for further treatment.

50 If the top α of the wood pieces is also to be cut, the circular saw 12 is used. In this case the wood pieces, after the root-end has been cut by the saw 11, are moved toward the opposite side of the device and then cut 55 by the saw 12 according to stops or the like placed in the runway. In such case the arms 13 and 16 to 21 may be situated at said opposite side of the device, or, if this is not the case, mechanisms may be provided to return 60 the wood pieces to the side where said arms are placed.

The arms 14 and 16 to 21 may also be arranged as the arms 14^a and 13, that is to say, they may normally be raised and then lowered by the wood piece which has to pass the 65

same. In this case the arm 16 should be placed near the outermost chain 5 and the arm 21 farthest away from the same.

Sorting according to length may be effected without moving the wood pieces longitudinally, as described above, if all ends of the pieces be placed close to a certain stop, as for instance E, Fig. 3, at the side of the sorting device opposite to the arms 16 to 21 and if said arms be placed at a distance 70 from the extension of said stop corresponding to the differences in length of the wood pieces in such manner that each piece raises only the corresponding arm 16 to 21.

As shown in Fig. 2, the chains 5 may extend above the chains 1 with the result that the wood may be supplied to the sorting device on runways B and C and then conveyed by the chains 5 to the end of the same designated by A in Fig. 1. 80

Sorting of the wood according to thickness, width, length and quality in different combinations of these properties may be effected by means of the devices shown in Figs. 8 to 13 inclusive, Figs. 8 to 11 showing particularly 90

a device for sorting according to thickness and width. In this device the arms 14 are placed on the shafts 15, the arms 16 to 21 being substituted by double arms 26 in Figs. 8 and 9 and 26^a in Figs. 10 and 11 each of 95

said arms being swingable about a pin 27. The end of each double arm 26 and 26^a directed away from the arriving wood is pro- 100

vided with a projection, a lug 29 or the like, adapted to strike, on the swinging move- 100

ment of the arm, against a crank 30 secured to the corresponding shaft 15 thus turning the shaft 15 or the arms 14 respectively to the position shown by stippled lines. At the 105

opposite end each arm 26 and 26^a is provided with a projection 31 extending in the longi- 110

tudinal direction of shaft 15 and positioned above the part of the runway where the cor- 115

responding ends of the wood pieces pass. The last named ends of the arms 26 and 26^a 110

and the projections 31 are so arranged that the lower surface of the projections are situ- 120

ated on different levels at the successive col- 120

lecting compartments. Owing thereto each 125

arm 26 and 26^a can only be actuated by wood 125

pieces of a certain thickness, the correspond- 125

ing arm 14 thereby being raised. Wood 125

pieces of less thickness pass below the pro- 125

jections 31 pertaining to wood pieces of 125

greater thickness without actuating the cor- 125

responding arms 26 and 26^a. Of course, the 125

device should be so arranged that the wood 125

pieces of greater thickness are separated be- 125

fore those of less thickness. 130

The sorting device may also be so con- 125

structed that all the arms 26 and 26^a bear 125

on the runway, while the distances between 125

the projections 29 and the cranks 30 vary 125

from one collecting compartment to another 125

If desired, the arms 26 may be of the shape shown in Fig. 9.

- Sorting according to width may be effected by varying the distance designated by a 5 in Figs. 10 and 11 between the inner edge of projection 31 and the line connecting the free ends of the arms 14. If said distance be smaller than the width of the wood piece, the arms 14 are kept raised, until the edge of 10 the wood piece enters the space below the raised ends of the arms 14, the wood piece then dropping down into the corresponding collecting compartment. If said distance be greater than the width of the wood piece, 15 the arms 26^a and 14 are lowered, before the edge of the wood piece reaches the space below the ends of the arms 14.
- If all the arms 26 and 26^a be placed in one straight line, sorting according to thickness 20 and width can obviously be effected without moving the wood pieces longitudinally, provided that the circular saw be placed in correct position in relation to the projections 31.
- 25 Combined sorting according to thickness, width and quality or length may be effected by providing in the runway different groups of arms 26 and 26^a, the position of said groups which represents different qualities 30 corresponding to the position of different directing lines 26¹ (Fig. 3) according to which the wood pieces are adjusted by being moved in longitudinal direction at the beginning of the runway, as stated above.
- 35 Figs. 12 and 13 illustrate a modified form of the device shown in Figs. 8 to 11 inclusive. At one end the arm 26^b is journaled on a pin 35 and at the other end by links 45 and 46 movably connected with an arm 47 se- 40 cured to a shaft 48 to which the arms 14 are attached. Journaled to the runway is a hook 49, one end of which is positioned above the runway in the path of movement of the wood, the other end being provided with a 45 notch 50 adapted to engage a pin 51 secured to the link 46. The arms 26^b are, as the arms 26 and 26^a in Figs. 8 to 11 respectively, provided with lateral projections. If an arm 26 be raised by the wood, the pin 51 50 enters the notch 50. If the distance between the edge of the projection 31 directed toward the arriving wood piece and the end of the hook 49 extending above the runway be greater than the width of the wood piece, the arm 26^b will be lowered before the hook 49 is turned by the wood piece, and the pin 51 then leaves the notch 50, the hook 49, 55 when turned, not actuating the arms 14 which remain at rest. Should, on the contrary, the said distance be smaller than the width of the work piece, the arms 14 are turned (Fig. 13). Consequently, said arms are turned only in case of wood pieces which are intended to drop down into the cor- 60 responding collecting compartment.

The sorting device described above may be modified in many respects without deviating from the principles of the invention. Thus for instance the wood pieces, in case of combined sorting, may pass first along a horizontal runway and drop down from the same 70 onto a longitudinal runway for each sort to be further sorted in several respects. Several arms 26 may coact and be actuated for sorting according to length, width and thickness 75 instead of a single arm as described above. If desired, the arms actuated by the wood may be provided with counter-weights in order to reduce as far as possible their resistance to the wood pieces fed forward. 80

Having now particularly described and ascertained the nature of my said invention and in what manner the same is to be performed, I declare that what I claim is:—

1. A sorting device for sawn wood, comprising a runway, collecting compartments located below said runway, and vertically movable sorting means disposed in the runway at the top of each compartment, said means closing the entrance thereto in one 90 position and opening the same in another position and adapted to control the entrance of the wood into the compartment.

2. A sorting device for sawn wood, comprising a runway, collecting compartments 95 located below said runway, and vertically movable sorting means disposed at the top of each compartment in the path of movement of the wood, said means closing the entrance to the compartment in one position 100 and opening the same in another position and adapted to be moved to open position by wood destined for the compartment.

3. A sorting device for sawn wood, comprising a runway, collecting compartments 105 located below said runway, and vertically swingable sorting means disposed at the top of each compartment in the path of movement of the wood, said means closing the entrance to the compartment in one position and opening the same in another position 110 and adapted to be swung to open position by wood destined for the compartment.

4. A sorting device for sawn wood, comprising a runway, collecting compartments located below said runway, means placed in the latter and serving to determine the longitudinal position of the wood pieces on the runway, and movable sorting means disposed in the runway at the top of each compartment, said sorting means closing the entrance thereto in one position and opening the same in another position and adapted to control the entrance of the wood into 120 the compartment.

5. A sorting device for sawn wood, comprising a runway, collecting compartments located below said runway, and vertically swingable sorting means disposed at the 130

top of each compartment in the path of movement of the wood, said means closing the entrance to the compartment in one position and opening the same in another position and adapted to be swung to open position by wood destined for the compartment.

6. A sorting device for sawn wood, comprising a runway, collecting compartments located below said runway, and vertically swingable arms disposed at the top of each compartment, shafts supporting said arms, said arms closing the entrance to the compartment in one position and opening the same in another position, and other arms secured to said shafts and adapted to be swung by a longitudinal side of the wood piece so as to move the first named arms to opening position.

7. A sorting device for sawn wood, comprising a runway for the wood pieces, collecting compartments below said runway, vertically swingable arms disposed at the top of each compartment, shafts supporting said arms, said arms closing the entrance to the compartment in one position and opening the same in another position, and other arms placed in the path of movement of the wood pieces and vertically swingable in relation to the runway and the shafts, said latter arms being adapted to be actuated by the wood pieces so as to swing the first named arms to opening position.

8. A sorting device for sawn wood, comprising a runway for the wood pieces, collecting compartments below said runway,

vertically swingable arms disposed at the top of each compartment, shafts supporting said arms, said arms closing the entrance to the compartment in one position and opening the same in another position, other arms placed in the path of movement of the wood pieces and vertically swingable in relation to the runway and the shafts, projections of different length extending from said latter arms in said path of movement, said projections being adapted to be actuated by the wood pieces so as to swing the first named arms to opening position.

9. A sorting device for sawn wood, comprising a runway, collecting compartments below said runway, vertically swingable arms disposed at the top of each compartment and closing the entrance to the compartment in one position and opening the same in another position, movable members placed above the runway in the path of movement of the wood pieces and connected with said swingable arms, said movable members causing, when actuated by the wood pieces, said swingable arms to open momentarily the entrance to the compartment, and other movable members placed on the runway in the path of movement of the wood pieces and adapted, when actuated by the same, to be connected with said swingable arms so as to keep them in opening position.

In testimony whereof I have signed my name.

GUSTAF EMANUEL JOHANSON.
